UNITED STATES PATENT OFFICE

GEORGE W. WALLACE, OF SAN FRANCISCO, CALIFORNIA, ASSIGNOR TO THE S. E. COMPANY, A CORPORATION OF DELAWARE

CARBONIZING APPARATUS

Application filed March 15, 1927. Serial No. 175,600.

This invention relates to carbonizing apparatus; and it comprises a carbonizing chamber of the top fired shaft kiln type constructed with a spaced outer supporting shell of any suitable material, such as steel plate, concrete brick work, etc. and an interior suspended kiln chamber or lining of refractory material, such as fire brick, spaced from the shell and carried thereby, the said lining being of greater diameter at its bottom than at the top for the purpose of facilitating withdrawal of spent shale, etc. after a carbonizing operation, the said lining being advantageously arched at its upper end to provide a dome-like construction and said lining being supported by, or on, projections such as angle iron members carried by the outer shell, or in the case of a brick work or concrete structure provided with a projection or projections to support said lining; all as more fully hereinafter set forth and as claimed.

Internally fired apparatus of the kiln type used for producing oil from shale, low temperature carbonization of coal, etc., and operating on successive charges of material is generally short-lived, expansion and contraction attendant on the temperature changes cracking and destroying it. It is an object of the present invention to provide more durable apparatus of this type and to this end I use a double-walled chamber; an outer shell and a liner spaced somewhat from it; with connecting and supporting means permitting differential expansion and contraction. The portion of the liner exposed to the greatest temperature change is suspended, allowing a limited amount of up-and-down play. In down draft operation, to which this invention is particularly applicable, the greatest wear is usually in the portion of the lining above the bottom and below the top. The spacing between liner and shell gives some thermal insulation.

In the accompanying illustration I have shown, more or less diagrammatically, an embodiment of my invention. In this showing:

Fig. 1 is a vertical cross-section of a carbonizing chamber;

Fig. 2 is a detail cross-section of a portion

of the furnace shown in Fig. 1, drawn on a larger scale; and,

Fig. 3 is a view similar to Fig. 2 of another portion of the furnace.

The carbonizing chamber shown in Fig. 1 comprises a shell or casing 1 of reinforced concrete, steel, or the like, supported on I-beams 2 and 3, and provided with a lining 4 of any suitable refractory material, spaced somewhat from the shell; the intervening space being indicated by 5. The liner may be made of fire brick or any other suitable refractory material. The space may be left vacant, forming an air chamber but advantageously I fill it with some good heat insulating material such as diatomaceous earth ("silocell", etc.). Angle irons 6 and 7 are carried by shell 1, the inwardly projecting portions of such angle irons serving as a footing for the refractory lining. Above these angle irons I have shown structural steel members 8, (see Fig. 3) which may be angle irons or T beams rigidly positioned in the casing 1 and projecting inwardly. These serve to support the mid-portion of the lining 4. Members 8 are disposed a relatively short distance above members 6 and 7, and thereby permit separate removal and replacement of the lower portion 9 of the lining 4 or of said mid-portion. This mid-portion requires repair or renewal oftener than the rest of the lining.

At or near its top the liner is provided with an arched or stepped off portion 10, forming a roof having the general appearance of a dome. As stated the liner is somewhat wider at the bottom than at the top to facilitate bottom removal of spent charges, this giving the liner as a whole the general shape of a truncated cone merging into the domed roof 10. This construction facilitates expansion and contraction of the liner as a unit, and the taper permits of quick and complete dumping of spent charges.

Structural steel members 11 illustrated in detail in Fig. 2, are secured to casing 1 adjacent the dome which has an offset resting upon them. Some of the weight of the liner is carried in suspension by these members 11, which also support the additional weight of

the dome carrying the air and gas inlets 17 and 18 and the fuel feeding device 15. As shown, the members 11 are formed with inwardly projecting flanges or webs 12, which extend underneath and contact with an overhanging offset 13 formed on the top 10. This construction possesses the advantage of providing a support for the roof which does not interfere with the longitudinal expansion or contraction of the liner as a whole. It also permits of the independent replacement or repair of the mid-portion of the liner without affecting the top. Renewal of the mid-portion or of the bottom portion of the shaft is by tearing down the brick or other refractory and replacing it.

Where the weights to be supported are great additional angle irons or supports may be positioned at intervals along the height of the liner.

Through the dome passes a hopper feed 15 into which shale, etc. may be supplied from car 16.

Pipes 17 and 18 enter the upper end of the chamber and serve to introduce air as a down draft. The heat necessary for operation may be furnished by combustion of carbon in upper layers by air thus introduced. Or air may be introduced by one pipe and gas by the other to produce flame and localized high temperature. Either the air or gas, or both, may be diluted with an endothermic agent—steam or products of combustion—to give better control of heating.

The apparatus shown is generally used in a special way of carbonizing in which a charge of shale is heated at the top till a more or less exothermic carbonizing reaction is instituted and this carbonizing reaction is then propagated downward as a traveling zone by regulation of the heat above. Tars, oils, etc. travel downward into and through cooler material ahead of this relatively hot zone and do not suffer secondary carbonization. Methods of this type are described and claimed in my Patent No. 1,536,696, May 5, 1925.

An inclined and slideable grate 19 is provided at the bottom of the chamber, and immediately beneath it and forming a part thereof is outlet pipe 20 for conducting off gases, vapors and liquids formed in operation. A valve 21 is provided in the pipe 20 for manually controlling the flow from pipe 20 to a main 22. This sliding grate permits quick and convenient removal of a spent charge.

What I claim is:

1. In an internally fired carbonizing apparatus of the shaft kiln type a partially suspended and partially supported shaft of refractory material having a supported integral dome top and a surrounding spaced sustaining shell carrying said shaft by means of angle irons, coal feeding means through the

top of said dome, an air inlet and a gas inlet in said dome and means at the bottom of the shaft for removing gases and vapors.

2. In an internally fired carbonizing apparatus of the shaft kiln type for carbonizing shale and the like, a vertical shell and a contained vertical dome topped shaft casing of refractory material and made of downwardly increasing diameter, spaced away from the outer shell and carried thereby, the main support being afforded at a point near the dome top whereby parts of the shaft casing therebelow are afforded a limited amount of up and down play.

3. In an internally fired carbonizing apparatus of the shaft kiln type for carbonizing shale and the like, a vertical weight-carrying shell provided with internal lugs near the top and near the bottom and a contained shaft casing of refractory material and of downwardly increasing diameter, spaced away from the outer shell, said shaft being provided with a closed top having an offset resting on the upper lugs, said shaft being thereby adapted to replacement of its mid-portion without removal of the top.

4. In an internally fired carbonizing apparatus of the shaft kiln type for carbonizing shale and the like, a weight-carrying outer shell of structural materials and carrying lugs near its top and near its bottom, and a contained integral shaft casing of refractory material, said casing having an integral closed top with an offset resting on the upper lugs and a lower middle portion supported by the lower lugs and adapted to independent removal and replacement.

5. In an internally fired down draft carbonizing apparatus of the shaft kiln type for carbonizing coal and the like, a vertical outer shell and a vertical internal shaft formed of refractory material and having an integral closed top, said internal shaft being spaced away from the outer shell and supported thereby, support being afforded at points somewhat below the closed top and also at points somewhat above the bottom of the shaft.

In testimony whereof, I have hereunto affixed my signature.

GEORGE W. WALLACE.
